FILLING-REPLENISHING LOOM.

1,267,168.

Specification of Letters Patent.

Patented May 21, 1918.

Application filed September 20, 1915. Serial No. 51,523.

To all whom it may concern:

Be it known that I, WILLIAM H. BAKER, a citizen of the United States, residing at Boston, in the county of Suffolk and State 5 of Massachusetts, have invented an Improvement in Filling-Replenishing Looms, of which the following description, in connection with the accompanying drawings, is a specification, like letters on the drawings 10 representing like parts.

The invention to be hereinafter described relates to filling replenishing looms, wherein the shuttle, including the spent filling carrier or bobbin, is automatically removed 15 from the loom and a fresh shuttle containing a filling carrier supplied with filling, is substituted.

In looms of this general character, it has heretofore been customary in order to properly effect the change of shuttles, to either 20 temporarily stop the loom operation, or slow it down. Either of these conditions, obviously, involves a loss of production; and an important feature of the present invention, 25 therefore, consists in the means whereby practical substitution of a shuttle having a filled carrier therein may be effected without interruption of the loom operation or changing its speed.

In filling replenishing looms wherein replenishment is effected by the substitution of a shuttle supplied with filling for the one previously in use, it has heretofore been customary to permit the outgoing or spent shuttle to find its own way from the shuttle-box to a shuttle receptacle for the spent shuttles. This has been the cause of considerable damage, and in many cases of the destruction of 35 the shuttles. Another important feature of the present invention, therefore, consists in a transerrer for taking a shuttle from a source of supply and delivering it to one of the cells of a two-cell shuttle-box, from the other cell of which the outgoing or spent shuttle is taken by the transerrer and delivered by it to the receptacle for the spent 40 shuttles.

In a loom of the filling replenishing type, it is desirable that the means for changing 45 the shuttles shall be normally inoperative and shall be made effective to change the shuttles only upon call for replenishment, and that thereupon, it shall be temporarily locked to the lay, in order that the incoming and outgoing shuttles may be trans-

ferred to and from operative relation with the shuttle-box. A further important feature of the present invention, therefore consists in means for normally maintaining the transerrer in inoperative position and to 60 cause such transerrer to move toward the lay and become detachably connected thereto upon call for replenishment, and after the shuttles have been changed, to be freed from such connection with the lay and caused to 65 resume its initial or original position.

Various other features of the invention, as well as novel combinations of parts will hereinafter be described in connection with the accompanying drawings which illustrate 70 a good, practical form of the present invention, it being understood, of course, that the details of the invention as illustrated and described, may be variously changed, within the true scope of the actual invention, which 75 is defined by the claims.

In the drawings:—

Figure 1 is a side elevation of a filling replenishing loom of the shuttle-changing type, with the parts shown in the position 80 they normally occupy when no replenishment is to be effected, some of the parts of the loom which are not necessary for an understanding of the invention, being omitted for purposes of clearness of illustration: 85

Fig. 2 is a view similar to that of Fig. 1, showing the position of parts when a call for replenishment has been made, and the transerrer has been moved into position for transferring a shuttle supplied with filling 90 to and taking the spent shuttle from operative relation with the weaving instrumentalities;

Fig. 3 is a view similar to that of Fig. 2, showing a more advanced step in the shuttle- 95 changing operation;

Fig. 4 is a front elevation at the filling replenishing side of the loom, containing features of the present invention, some of the parts being broken away for the purpose of 100 more clearly illustrating those beyond;

Fig. 5 is a detail view on an enlarged scale, showing a safety device to prevent operation of the shuttle-changing mechanism when a shuttle fails to be properly boxed; 105 and

Fig. 6 is a detached detail showing the transerrer and some of its associated parts.

Looms of the filling replenishing type, which are sometimes known as automatic 110

2
looms, either effect replenishment of the filling when that in the active shuttle has become exhausted to a predetermined extent, or when the filling of the shuttle in play becomes broken. To effect replenishment under either of these conditions, certain "feeler" and "detecting" mechanisms are employed which usually effect a rocking movement of a part which calls into play or initiates the replenishing operation. In the illustration of the present invention the "feeler" and "detecting" means are not shown, because such means are well known by those skilled in the art and their particulars of structure form no essential part of the present invention.

The loom frame 1 may be of any usual or desired character suitable for supporting the operating parts, and as shown, it has mounted thereon in suitable bearings 2, a crank shaft 3 to which the lay 4 is connected by a pitman or connecting rod 5, said lay being mounted as usual on the lay swords 6 sustained upon the rocking shaft or stud 7. The shuttles carrying the supply of filling may be contained in any suitable form of hopper; and in the present instance, the said hopper comprises the shuttle-end-engaging parts 8, Figs. 1 and 4, suitably sustained from the loom frame as by means of the bracket arms 9, the construction being such that the shuttles 10, Fig. 4, may have their ends suitably contained between the shuttle-end-engaging parts 8, the ends of the filling 35 11 extending from the filling carriers in the shuttle being preferably secured to some fixed part, as 12, Fig. 4.

In order that the columns of shuttles in the hopper may be suitably sustained there 40 in and the lower shuttles of the series be permitted at a suitable time to take position in the transferrer, the lower portion of the hopper is provided with the slide 13 having a stop portion such as 14 for engaging beneath the end portions of the lower shuttle. The slide 13 is provided with an opening at each end through which pass the parallel actuating rods 15, the horizontal connecting portion 16 of which may be suitably sus 45 tained in the brackets 17 projecting from the front wall of the hopper, as indicated in Figs. 1 and 4. The parallel actuating arms 15 for the slide are normally under the influence of a spring tending to cause the 50 slide to move to the left, Fig. 1, in which position the projection on the slide is in the path of the end portions of the lowermost shuttle, but permits such slide to be moved to the right, Fig. 1; as will hereinafter more 55 fully appear, to permit the lowermost shuttle in the hopper to drop in position for engagement by the transferrer. This spring may be of any suitable form, but as shown in the present illustrated form of the invention, comprises the leaf spring 18 which

overlies one of the parallel arms 15 of the actuator.

Mounted in a suitable arm 19, Figs. 1 and 2, loosely carried upon the stud or shaft 7, is the transferrer. In the present illustrated form of the invention, such transferrer comprises the upwardly-extending arms 20 secured by suitable means such as the bolt 21 to the part 19 and capable of rocking with said part 19 about the stud or shaft 7 as an axis. The upwardly-extending arms 20, Fig. 4, are bent into divergent relation at their upper portion, as shown at 22, to an extent sufficient to permit a shuttle to pass between the side portions 23 thereof, the construction being such that when spent shuttle is to be discharged from the loom it may pass between the side portions 23 of the transferrer.

The side portions 23 of the transferrer have their upper ends turned rearwardly, as indicated at 24, so as to embrace between them the full length of the shuttle to be transferred. The terminal end portions 25 are turned toward each other to form a rear seat for one side wall of the shuttle. Pivotally mounted at 26, on each of the side portions 23 is a bell crank lever, one arm 27 of which carries a shuttle-clamping member 28 adapted to engage the side of the shuttle opposite the bent portions 25 of the transferrer. The springs 29 normally act upon the bell cranks to move their shuttle-clamping portion 28 into clamping relation with the shuttle placed between them and the end portions 25 of the transferrer. Each of the bell cranks has a forwardly-projecting toe portion 30, Fig. 2, adapted to engage a pin 31, one of which is mounted on a bracket 32 rising from the shuttle receptacle 33 carried by the loom frame, and the other of which projects from the loom frame 1, substantially as indicated in Fig. 4, the construction being such that when the transferrer is moved from the position shown in Fig. 2 toward the front of the loom, the rounded upper surface portion of the toes 30 of the bell cranks will engage beneath the pins 31 and cause the bell crank to be moved about its pivotal mounting 26 to separate the shuttle clamping member 28 from the end portions 25 of the transferrer and permit the lowermost shuttle in the hopper to drop between the clamping members of the transferrer, substantially as indicated in Fig. 1.

In order to position the lowermost shuttle properly between the clamping members 25 and 28 of the transferrer, a shelf 34 is provided below the bottom portion of the hopper to catch the lowermost shuttle when it is dropped from the hopper and hold it in position for the action of the clamping members of the transferrer, substantially as indicated in Figs. 1 and 2. In order to actuate the slide 13 to permit the lowermost

shuttle in the hopper to drop upon the shelf 34 between the clamping members of the transfferer as the latter moves toward the front of the loom after having transferred 5 a shuttle to the shuttle-box, one of the side portions 23 of the transfferer is provided with a pin 35 adapted to strike one of the parallel arms 15 of the slide actuator when the transfferer moves from its rear toward 10 its front position, the construction being such that the actuator for the slide will be moved toward the front to thereby permit the lowermost shuttle in the hopper to drop onto the shelf 34 between the clamping members 15 of the transfferer. For normally holding the transfferer in its front or inoperative position as indicated in Fig. 1, a suitable spring 36 may be provided, one end of 20 which is connected to a bracket pin 37 and the other to a pin 38 projecting from the upright members 20 of the transfferer.

From the construction thus far described, it will be apparent that when the transfferer is in its front position as indicated in Fig. 25 1, the clamping members 25 and 28 will be separated to permit a shuttle 10 to drop between them; but when the transfferer is moved rearwardly to carry a shuttle into 30 position to be transferred to the shuttle-box, 35 and the end portion 30 of the bell cranks are disengaged from their pins 31, the springs 29 will turn the bell cranks upon their pivotal mounting and cause the shuttle to be clamped and held between the clamping members 25 and 28.

As hereinbefore indicated, the present invention contemplates a two cell shuttle-box to coöperate with the transfferer to effect a transfer of a shuttle containing a supply of 40 filling and the removal of the shuttle containing the spent filling carrier. Such two cell shuttle-box may be variously formed, but in the present instance, it comprises an upper box 39 and a lower box 40 which are secured to the rods 41 by suitable means such as the bolts 42. In the present form of the invention, two such rods 41 for supporting the two cell shuttle-box are employed, one being preferably located adjacent each end 45 of the shuttle-box, but it is manifest that the number may be varied to suit the conditions of use.

The shuttle-box-carrying rods 41 are mounted for vertical movement in the lugs 43 carried by the lay 4; and in order that the shuttle-box-carrying means such as the rods 41 may be appropriately moved in their bearings 43 to change the positions of the two cells of the shuttle-box as will herein- 50 after more fully appear, the present invention contemplates normally inactive means which shall be made operative upon call for filling replenishment, to effect the change in the cells of the shuttle-box. As one means 55 to this end the rods 41 are secured to a mem-

ber 44, Figs. 1 and 4, which constitutes a connecting member for said rods that they may be moved in unison. As one form of means for connecting the shuttle-box supporting rods 41 with the member 44, the latter is provided with bearing portions 45, Fig. 4, through which the rods 41 extend and to which they may be secured by means of clamp nuts or bolts, such as 46, Fig. 1, the construction being such that upon rising 75 and falling movement of the member 44 the rods 41 will be caused to move in unison therewith.

The member 44 is operatively connected to means for reciprocating it and perforce, the supporting rods 41 in order to change the position of the shuttle box cells upon the call for filling replenishment. As one form of means to this end, one of the supporting rods 41 is extended below the member 44 to 85 which it is secured, and has slidingly mounted thereon the collar 47, Fig. 1, said collar 47 being normally held against a shoulder 48 on the rod 41 by means of a spring 49, the upper end portion of which, Fig. 1, finds 90 a seat against the under surface of the collar 47 and the lower end portion of which is seated upon the adjusting nuts 50, the construction being such that should the collar 47 be moved downwardly and the two cell 95 shuttle-box be free to such movement, they will be moved downwardly to bring the upper shuttle-box into the line of the race, or into the position formerly occupied by the lower shuttle-box; but should an obstruction 100 be presented to such movement of the shuttle-boxes, then the spring 49 would be compressed without movement to the shuttle boxes.

As one form of means for operating the 105 collar 47, there is provided a lever 51 pivotally mounted at one end as at 52 upon the machine frame, and having its free end connected at 53 to a rod 54, the upper end of which is connected to the collar 47 as at 55.

Suitably supported on the machine frame 110 is the lower or cam shaft 56 carrying a cam 57 which at times is permitted or caused to actuate the lever or arm 51. In the present instance, the arm 51 has pivotally mounted 115 thereon, the rocker 58 carrying a roll 59 adapted at times to be engaged by the cam 57. The rocker 58 is provided with a pin 60 which engages a slot 61 in the rocker controller or lever 62 pivoted at 63 to the machine frame, the construction being such that upon movement of the rocker controller or lever 62 contra-clockwise, Fig. 1, the rocker 58 will be moved upon its pivotal mounting to bring the roll 59 into coöperating 120 relation with the cam 57 on the lower or cam shaft.

Extending from the rocker controller or lever 62 is an arm 64 which may be conveniently connected to the rocker controller 125

in any suitable manner to project its end portion 65 into the path of a pin or roller 66 carried by an arm 67 for causing the rocker controller to be moved upon its pivotal support contra-clockwise, viewing Fig. 1, as will more fully appear. A stop 68, Fig. 1, may be provided on the lever or arm 51 to determine the movement of the lever or rocker 58 and define its operative relation with the cam 57, though of course this may not be necessary.

Pivotedly mounted at 69 is a latch lever 70 having one end 71 thereof connected by a spring 72 with the arm or lever 51 and its opposite end portion provided with a projection or roller 73 adapted to engage a recess 74 in the arm 67 under conditions as will hereinafter be made clear. The spring 72 normally acts upon the arm or lever 51 to hold the collar 47 against the shoulder 48 and the latch lever 70 in position indicated in Fig. 1 with its upper edge portion bearing against the stop 75.

Adjustably secured to the upright members 20 of the transerrer is the rearwardly-extending arm 67, hereinbefore described, the rear end portion of which carries the pin or roller 66 and is provided with the recess or depression 74, hereinbefore described.

The arm 67 may be appropriately connected to the members 20 of the transerrer adjustably in any suitable manner, but as indicated in the drawings, such connection is effected by means of the set screws 76, Figs. 1 and 2.

Mounted upon the arm 67 for movement longitudinally thereof, is a sleeve 77. A spring 78 having one end connected to the sleeve 77 at 79 and the other end connected at 80 to the members 20 of the transerrer, normally holds the sleeve 77 against a stop 81, said spring and sleeve 77 being for a purpose as will presently appear.

Pivotedly mounted upon the sleeve 77 is a hook 82 having a pin 83 projecting from the side thereof which normally rests upon the end of a lifter 84 which is itself connected to a sleeve or hub 85 secured to the usual transverse shaft 86, the construction being such that when the transverse shaft 86 is rocked clockwise, as is usual in filling replenishing looms, upon a call for filling replenishment, the lifter 84 will be raised and the hook 82 controlled thereby, will also be raised.

Extending downwardly from the lower portion of the lay is a bunter 87, Figs. 1 and 2, adapted to engage the hook 82 when the latter is lifted upon call for filling replenishment, as hereinbefore noted, the construction being such that when filling replenishment is indicated and the transverse shaft 86 is consequently rocked, the hook 82 carried by the sleeve 77 will be raised into position for engagement by the bunter 87 mount-

ed on the lay, as the latter moves rearwardly toward its back position, and as the lay thus reaches its back position the transerrer connected by the spring 78 to the sleeve 77 will have been moved backward from the position indicated in Fig. 1 to that indicated in Fig. 2.

When the transerrer has been thus moved into the position indicated in Fig. 2, the arm 67, as hereinbefore explained, will have been moved rearwardly to cause the pin 66 to rock the rocker controller 62 and bring the rocker 58 into position for operative engagement with the cam 57. Also at this time, the roller 73 on the latch 70 will have engaged the recess 74 in the arm 67 to thereby maintain the transerrer in the position indicated in Fig. 2, as the lay moves toward the front position again.

As the lay beats up or moves toward its front position after filling replenishment has been called, as indicated by Fig. 2, it is desirable that the transerrer be temporarily locked to the lay in order that it may partake of the lay movement during the time sufficient for the interval of transfer of the shuttle supplied with filling and the discharge of the spent shuttle. To this end, there is mounted upon the member 44, a catch 88 which is ordinarily above the top portion of the stop 81 which is provided with a shouldered portion 89; and as the lay moves forward into the position indicated by Fig. 3, with the transerrer related to the shuttle-boxes for transfer and removing of shuttles, the shuttle-box actuating mechanism hereinbefore described starts to lower the shuttle-boxes and thereby carry the catch 88 in front of the shouldered portion 89 of the stop 81 and lock the transerrer and lay together. The lay, however, continues to move forward to some slight extent after such locking position of the lay and the transerrer has occurred, and thereby disengages the roller 73 of the latch 70 from the recess 74 of the arm 67.

When the lay and transerrer have thus been locked together and the shuttle-boxes are moved downward as hereinbefore noted, the shuttle with the fresh supply of filling is removed from the transerrer and placed in the top cell of the shuttle-box, as indicated in Fig. 3, while the shuttle previously in play and contained in the lower shuttle-box is carried downward until the shuttle in the top cell is brought into the line of the race. At this time the catch 88 has moved downward with respect to the shoulder 89 on the stop 81 and becomes disengaged therefrom, whereupon the transerrer is detached from locking engagement with the lay, and under the influence of its spring 36 is returned to normal position, as indicated in Fig. 1, and a new or fresh shuttle drops be-

tween the clamping portions of the trans-
ferrer, as hereinbefore described.

As hereinbefore described, it is one of the purposes of the present invention to positively and effectively remove the spent shuttle from the loom. To effect this purpose, the lay 4 is provided with a lower recessed portion 90, as indicated by dotted lines in Figs. 1 and 3, adapted to receive the arms 91 extending rearwardly from and supported by the upright members 20 of the trans-
ferrer, Figs. 1, 2 and 3. The arms 91 which may be termed the "spent shuttle removing arms," are provided with the upwardly-projecting portions 92 and the recessed portion of the lay is such as to accommodate said arms. When the parts are in normal operative position before call for filling replenishment, it will be noted that the arms 91 will extend somewhat into the recessed portion 90 of the lay 4, as the lay moves to its front position. When, however, filling replenishment is called, and the trans-
ferrer is moved rearwardly in the position indicated in Fig. 2, the arms 91 will penetrate farther into or toward the rear of the lay 4 into position substantially as indicated in Fig. 3, and as the shuttle-box is lowered as hereinbefore described, the spent shuttle in the lower shuttle-box will pass in front of the upwardly-projecting portions 92 of the spent shuttle removing arms, and as the trans-
ferrer and lay are released from the locking engagement hereinbefore noted, and the trans-
ferrer returns to initial position, as indicated in Fig. 1, the arms 92 will engage the shuttle in the lower shuttle-box and positively remove it therefrom and deposit or throw the same into the shuttle receptacle 33. To enable the spent shuttle removing arms 92 to act in the manner described, the rear and bottom wall portions of the lower shuttle-box are properly slotted to permit the passage of the upright members 92 of said arms.

As hereinbefore noted, the shuttle supplied with filling has been deposited in the upper shuttle-box and then, by downward movement of the shuttle-boxes, it has been brought onto the line of the race. When the lay is in proper rear position, the picking action takes place as usual, the shuttle at this time being in the upper box, but said box being in lowered position. To effect the picking action, a picker mechanism of suitable construction may be employed, and as illustrated in the drawings, may comprise the picker staff 93 provided with a usual or preferred form of picker 94, the top wall of the upper shuttle-box being properly recessed as at 95 to permit the picking action of the picker and picker staff. After the shuttle has been picked from the top cell and before it is returned to that side of the

loom, the shuttle-box operating mechanism 65 will have returned the cells of the shuttle-
box to their normal operative position, that is, with the lower cell on the line of the race and the upper cell in position to receive a shuttle from the trans-
ferrer upon a subsequent call for filling replenishment. 70

It is desirable of course that should the shuttle not be properly boxed when replenishment is to be effected, such replenishment may be suspended; and to this end the lay 75 4 has mounted thereon a pin 96, Fig. 5, the head portion 97 of which is normally flush with the race 98. Pivotaly mounted in the lay 99 is an arm 100, the end of which is connected to the pin 96, the construction being such that should a shuttle be properly boxed on call for filling replenishment, the pin 96 may freely rise and permit oscillatory movement of the arm 100; but should a shuttle be not properly boxed, then 85 the pin 97 will meet the shuttle and fail to rise.

To effect this feeling action of the pin 96 upon call for filling replenishment, there is mounted upon the trans-
ferrer, a spring 101, 90 Figs. 1, 2 and 3, which projects rearwardly therefrom and has an inclined end portion substantially as indicated in Fig. 2, said inclined end portion being adapted to engage the arm 100 when the trans-
ferrer is in 95 rearward position, as indicated in Fig. 3, upon forward movement of the lay, the construction being such that should a shuttle be not properly boxed as the lay beats up upon call for filling replenishment, the arm 100 will meet the spring 101 and fail to be raised by it. In order to utilize this failure of movement of the arm 100 to prevent filling replenishment under such conditions, there is mounted upon the lay, as at 102, 105 Figs. 1 and 2, a hook 103, the end portion of which overlies the arm 100, substantially as indicated in Fig. 2. The hooked portion of the hook 103 is adapted to be normally engaged with a pin 104, Fig. 2, which pin is 110 secured to the member 44 connected with the shuttle-box moving rods. Upon call for filling replenishment, it will be noted that should the shuttle be properly boxed, the hook 103 will, upon forward movement of 115 the lay, be disengaged from the pin 104 and the shuttle-box operating mechanism be permitted to operate. Should, however, a shuttle be trapped or not be properly boxed, then, on the forward movement of the lay, 120 the pin 96 will prevent movement of the arm 100 and, perforce, of the hook 103, and the said hook will continue to lock the shuttle-boxes from movement responsive to their actuating means, and consequently re- 125 plishment will not be effected.

Various changes may be made in the form and character of some of the parts, within

the true scope of the invention as defined by the claims; but the means hereinbefore noted as a convenient embodiment of the present invention is found to be practical and efficient.

5 What is claimed is:—

1. In a filling replenishing loom, the combination of the lay having a shuttle-box provided with two cells at the replenishing side thereof, a hopper for supplying shuttles to be transferred to said shuttle-box, a trans- 10 ferrer for transferring a shuttle from the hopper to the shuttle-box, means operative upon call for filling replenishment for mov- 15 ing the transerrer toward the lay into operative relation with the said shuttle-box, means for moving the shuttle-box relative to the lay as the latter moves toward front position, means movable with the shuttle- 20 box to positively remove the shuttle from the transerrer into the normally inoperative cell of the shuttle-box, and means carried by the transerrer to engage the spent shuttle and remove it from the shuttle-box 25 as the transerrer returns to normal position.

2. In a filling replenishing loom, the combination of the lay having a two-cell shuttle- 30 box at the replenishing side of the loom, a hopper to contain a series of shuttles to be transferred to the shuttle-box, a transerrer provided with means for grasping a shuttle and carrying it from the hopper toward the lay into a position for transfer to the upper 35 cell of the shuttle-box, and means for lowering the shuttle-box to take the shuttle from the transerrer.

3. In a filling replenishing loom, the combination of the lay having a shuttle-box 40 provided with an upper and a lower cell, means normally acting to hold the shuttle-box with the lower cell on the line of the race, a transerrer, means operative on call for filling replenishment to move the trans- 45 ferrer toward the lay to place a shuttle in the upper cell of the shuttle-box, means for lowering the shuttle-box to place the upper cell on the line of the race and means movable with the shuttle-box to positively re- 50 move the shuttle from the transerrer into the upper cell of the shuttle-box, and means carried by the transerrer for engaging the spent shuttle and removing it from the lower cell of the shuttle-box after the transfer of 55 the shuttle into the upper cell has been effected.

4. In a filling replenishing loom, the combination of the lay having a shuttle-box provided with an upper and a lower cell, means 60 normally acting to hold the shuttle-box with the lower cell on the line of the race, a transerrer having shuttle grasping means, means operative on call for filling replenishment to move the transerrer toward the 65 lay to place a shuttle in operative relation

to the upper cell of the shuttle-box, means for lowering the shuttle-box to place the upper cell on the line of the race and to remove the shuttle from the transerrer into the upper cell of the shuttle-box, and means 70 carried by the transerrer for engaging the spent shuttle and removing it from the lower cell of the shuttle-box after the transfer of the shuttle into the upper cell has been effected, said shuttle-box lowering means act- 75 ing to return the lower cell to the line of the race after the shuttle has been picked from the upper cell of the shuttle-box.

5. In a filling replenishing loom, the combination of the lay provided with a shuttle- 80 box having an upper and lower cell the latter of which is normally on the line of the race, a transerrer provided with means for clamping and transferring a shuttle from a source of supply into the upper cell of the 85 shuttle-box and provided with means for engaging the spent shuttle in the lower cell of the shuttle-box, and means for relatively moving the shuttle-box and transerrer to transfer the fresh shuttle to the upper cell 90 and to positively remove the spent shuttle from the lower cell of the shuttle-box as the transerrer moves to initial position.

6. In a filling replenishing loom, the combination of the lay provided with a recess 95 in the front thereof, a two celled shuttle-box, means for raising and lowering said shuttle-box, a transerrer for transferring a shuttle from a source of supply and positioning it in the upper cell of the shuttle-box and having 100 spent shuttle removing arms to enter the recess in the front of the lay below the lower cell of the shuttle-box and engage the spent shuttle in said cell, and means for moving the transerrer relat... to the shuttle-box 105 to cause said spent shuttle engaging arms to positively remove the spent shuttle from the lower cell of the shuttle-box.

7. In a filling replenishing loom, the combination of the lay provided with a recess 110 in the front thereof, a two celled shuttle-box, means for raising and lowering said shuttle-box, a transerrer, means for moving the transerrer rearwardly for transferring a shuttle from a source of supply into the 115 upper cell of the shuttle-box and having spent shuttle removing arms projecting rearwardly therefrom to enter the recess in the front of the lay below the lower cell of the shuttle-box when the transerrer is 120 moved rearwardly and engage the spent shuttle in said cell, fingers carried by said arms to engage behind the spent shuttle, and means for moving the transerrer to cause said spent shuttle-engaging arms to 125 remove the spent shuttle from the lower cell of the shuttle-box.

8. In a filling replenishing loom having a lay and shuttle-box, a transerrer for trans- 130 ferring a shuttle from a source of supply

- to said shuttle-box, comprising, in combination, pivotally mounted arms having diverging upper portions to permit the passage of a spent shuttle between them, a shuttle 5 clamp carried by the upper portions of said arms for carrying a shuttle from the source of supply to said shuttle-box, spent shuttle engaging means carried by the transferrer to engage and remove the spent shuttle, and 10 means for relatively moving the shuttle-box and transferrer to transfer a fresh shuttle to the shuttle-box and effect positive removal of the spent shuttle while the loom continues in normal operation.
- 15 9. In a replenishing loom, the combination of the lay provided with a shuttle-box having two cells one of which is normally on the line of the race, a transferrer for transferring a shuttle with a supply of filling from a source of supply into the shuttle-box while the loom continues in operation, clamping means movable with the transferrer to grasp a shuttle and hold it in position to enter the upper cell of the shuttle-box as the lay beats up, and means for relatively moving the shuttle-box and transferrer to transfer the fresh shuttle to the cell of the shuttle-box normally out of line with the race.
- 20 10. In a filling replenishing loom, the combination of the lay provided with a shuttle-box having an upper and a lower cell at the replenishing side of the loom, a transferrer for grasping a shuttle at the 25 source of supply and carrying it toward the lay, means for temporarily locking the transferrer to the lay, means for lowering the shuttle-box to take the shuttle from the transferrer and then unlocking the transferrer from the lay, and means for restoring the transferrer to initial position.
- 25 11. In a filling replenishing loom, the combination of the lay provided on the filling replenishing side with a shuttle-box having an upper and lower cell, a transferrer for transferring a shuttle from a source of supply to the upper cell of the shuttle-box, means operative upon call for filling replenishment for moving the transferrer into 30 operative relation with the upper cell of the shuttle-box as the lay moved to back position, means for temporarily locking the transferrer in said position as the lay moves forward from back position, and means 35 operative as the lay moves forward for lowering the shuttle-box to cause the upper cell to remove the shuttle from the transferrer and permit the transferrer to return to initial position.
- 35 12. In a filling replenishing loom, the combination of the lay provided on the filling replenishing side with a shuttle-box having an upper and lower cell, a transferrer for transferring a shuttle from a source of supply to the upper cell of the shuttle-box,
- means operative upon call for filling replenishment for moving the transferrer into operative relation with the upper cell of the shuttle-box as the lay moves to back position, means for temporarily locking the transferrer in said position as the lay moves forward from back position, and means operative as the lay moves forward for lowering the shuttle-box to cause the upper cell to remove the shuttle from the transferrer and permit the transferrer to return to initial position. 70
- 40 13. In a filling replenishing loom, the combination of the lay having a shuttle-box, a transferrer for transferring a shuttle from a source of supply to the shuttle-box, means operative upon call for filling replenishment for moving the transferrer backward from its normal position as the lay moves to back position, a temporary lock for holding the transferrer in such back position as the lay moves toward front position, means for locking the transferrer to the lay as the lay approaches front position, and means for lowering the shuttle-box and to take a shuttle 75 from the transferrer and permit the latter to move to initial position.
- 45 14. In a filling replenishing loom, the combination of the lay having a shuttle-box provided with an upper and lower cell, a transferrer, interengaging parts carried by the lay and transferrer and operative upon call for filling replenishing for moving the transferrer rearwardly from normal position as the lay moves to back position, a temporary lock for holding the transferrer in rear position as the lay moves frontwardly, a lock for connecting the lay and transferrer when the temporary lock is released, and means for moving the shuttle-box to cause the shuttle carried by the transferrer to be transferred to the upper cell of the shuttle-box and the transferrer to be unlocked from the lay. 80
- 50 15. In a filling replenishing loom, the combination of the lay having a shuttle-box provided with an upper receiving and a lower service cell, means for normally holding the shuttle-box with the lower service cell on the line of the race, a transferrer for transferring a shuttle from a source of supply to the upper receiving cell of the shuttle-box, means operative upon call for filling replenishment for lowering the shuttle-box to cause the shuttle held by the transferrer to be taken 85 therefrom by the upper receiving cell and carried down to the line of the race, and means to prevent such movement of the shuttle-box when the spent shuttle is not properly boxed in the lower service cell thereof 90 when replenishment is called.
- 55 16. In a filling replenishing loom, the combination of the lay having a shuttle-box provided with an upper receiving and a lower service cell, means for normally holding the shuttle-box with the lower service cell on the line of the race, a transferrer for transferring a shuttle from a source of supply to the upper receiving cell of the shuttle-box, means operative upon call for filling replenishment for lowering the shuttle-box to cause the shuttle held by the transferrer to be taken 95 therefrom by the upper receiving cell and carried down to the line of the race, and means to prevent such movement of the shuttle-box when the spent shuttle is not properly boxed in the lower service cell thereof 100 when replenishment is called.
- 60 17. In a filling replenishing loom, the combination of the lay having a shuttle-box provided with an upper receiving and a lower service cell, means for normally holding the shuttle-box with the lower service cell on the line of the race, a transferrer for transferring a shuttle from a source of supply to the upper receiving cell of the shuttle-box, means operative upon call for filling replenishment for lowering the shuttle-box to cause the shuttle held by the transferrer to be taken 105 therefrom by the upper receiving cell and carried down to the line of the race, and means to prevent such movement of the shuttle-box when the spent shuttle is not properly boxed in the lower service cell thereof 110 when replenishment is called.
- 65 18. In a filling replenishing loom, the combination of the lay having a shuttle-box provided with an upper receiving and a lower service cell, means for normally holding the shuttle-box with the lower service cell on the line of the race, a transferrer for transferring a shuttle from a source of supply to the upper receiving cell of the shuttle-box, means operative upon call for filling replenishment for lowering the shuttle-box to cause the shuttle held by the transferrer to be taken 115 therefrom by the upper receiving cell and carried down to the line of the race, and means to prevent such movement of the shuttle-box when the spent shuttle is not properly boxed in the lower service cell thereof 120 when replenishment is called.
- 70 19. In a filling replenishing loom, the combination of the lay having a shuttle-box provided with an upper receiving and a lower service cell, means for normally holding the shuttle-box with the lower service cell on the line of the race, a transferrer for transferring a shuttle from a source of supply to the upper receiving cell of the shuttle-box, means operative upon call for filling replenishment for lowering the shuttle-box to cause the shuttle held by the transferrer to be taken 125 therefrom by the upper receiving cell and carried down to the line of the race, and means to prevent such movement of the shuttle-box when the spent shuttle is not properly boxed in the lower service cell thereof 130 when replenishment is called.

- shuttle-box with the lower service cell on the line of the race, a transferrer for transferring a shuttle from a source of supply to the upper receiving cell of the shuttle-box, means operative upon call for filling replenishment for lowering the shuttle-box to cause the shuttle held by the transferrer to be taken therefrom by the upper receiving cell and carried down to the line of the race, a 70
- 10 device having a shuttle feeling portion normally maintained on the line of the race, means carried by the transferrer for moving said device above the line of the race when replenishment is called and the spent 75
- 15 shuttle is properly boxed, and means to prevent such movement of the shuttle-box when the spent shuttle is not properly boxed in the lower service cell thereof when replenishment is called. 80
- 20 17. In a filling replenishing loom, the combination of the lay and shuttle-box, a transferrer having a backwardly extending arm, means operative on call for filling replenishment for moving the transferrer backward 85
- 25 ward from normal position, a catch for engaging said arm and holding the transferrer temporarily in back position and adapted to release the transferrer as the lay moves forward, means for locking the lay and 90
- 30 transferrer together when the transferrer is released from the catch, and means for unlocking the transferrer from its connection with the lay after a shuttle with a fresh supply of filling has been transferred to the 95
- 35 shuttle-box.
18. In a filling replenishing loom, the combination of the lay provided with a shuttle-box having an upper receiving and a lower service cell, a transferrer having a backwardly-extending arm, means operative upon call for filling replenishment for moving the transferrer backward from front position, a catch for temporarily locking the transferrer in back position, and means 100
- 40 rendered effective by backward movement of said arm for lowering the shuttle-box to cause the upper receiving cell to take a shuttle from the transferrer. 105
19. In a filling replenishing loom, the combination of the lay provided with a shuttle-box having an upper receiving and a lower service cell, a transferrer having a backwardly-extending arm, a sleeve 110
- 45 yieldingly mounted on said backwardly-extending arm, a hook connected to said sleeve, a bunter carried by the lay, an arm for controlling the position of the said hook and operative on call for replenishment for raising the hook into the path of the bunter to 115
- 50 move the transferrer rearwardly, and means rendered operative by such rearward movement of the transferrer for causing the upper receiving cell of the shuttle-box to take a shuttle from the transferrer. 120
- 55 20. In a filling replenishing loom, the combination of the lay provided with a shuttle-box having an upper receiving and a lower service cell, a transferrer having a backwardly-extending arm, means operative upon call for filling replenishment for moving the transferrer backward from front position, a catch for temporarily locking the transferrer in back position, and means rendered effective by backward movement of said arm for lowering the shuttle-box to cause the upper receiving cell to take a shuttle from the transferrer and to lower the spent shuttle, and means carried by the transferrer for engaging the spent shuttle when thus lowered to remove it from the 125
- 60 service cell. 130
21. In a filling replenishing loom, the combination of the lay provided with a shuttle-box having an upper and a lower cell one of which is normally on the line of the race, a hopper to contain a series of shuttles to be transferred to the shuttle-box, a transferrer for transferring a shuttle having a supply of filling from the hopper to one of said cells, means for locking the transferrer to the lay for movement therewith during the transfer of the shuttle to the cell of the shuttle box, and means for shifting the shuttle-box to place the fresh shuttle on the line of the race and then return it to normal position out of line with the race after the fresh shuttle is picked. 135
22. In a filling replenishing loom, the combination of a lay and shuttle-box, a hopper to contain a series of shuttles, a transferrer for transferring a shuttle having a supply of filling from the hopper to the shuttle-box, and means movable with the transferrer toward and from front position for positively removing the spent shuttle from the service shuttle-box as the transferrer returns to initial position. 140
23. In a filling replenishing loom, the combination of the lay provided with a shuttle-box having two cells at the replenishing side of the loom one of which is normally on the line of the race and the other of which is normally out of line with the race, a hopper for containing a series of shuttles, a transferrer for transferring a shuttle from the hopper to the cell of the shuttle-box normally out of line with the race, means for locking the transferrer temporarily to the lay for movement in unison therewith during the transfer of the shuttle to the cell of the shuttle-box normally out of line with the race, means for moving the shuttle-box to carry the spent shuttle out of line with the race and the fresh shuttle onto the line of the race and returning the shuttle-box to normal position after the fresh shuttle is picked. 145
24. In a filling replenishing loom, the combination of a lay and shuttle-box, a hopper to contain a series of shuttles, a 150

transferrer for transferring a shuttle having a supply of filling from the hopper to the shuttle-box, a clamp carried by the transferrer for taking a shuttle from the 5 hopper, means for actuating the transferrer to carry the clamped shuttle to transferring position, and means for opening the clamp to permit another shuttle to pass from the hopper to the control of the transferrer 10 when the latter returns to initial position after a transfer.

25. In a filling replenishing loom, the combination of the lay having a two cell shuttle-box, one of said cells being normally 15 on the line of the race, a hopper for a series of shuttles, a transferrer for taking a shuttle from the hopper and placing it in the cell of the shuttle-box which is normally out of line with the race, means for causing the 20 transferrer and lay to move in unison on call for replenishment, and means operative as they move in unison to move the shuttle-box relative to the transferrer to shift the position of the cells, and then return them 25 to normal position.

26. In a filling replenishing loom, the combination of the lay having a two cell shuttle-box, one of said cells being normally on the line of the race, a hopper for a series 30 of shuttles, a transferrer for taking a shuttle from the hopper and placing it in the

cell of the shuttle-box which is normally out of line with the race, means for causing the transferrer and lay to move in unison on call for replenishment, and means operative 35 as they move in unison to move the shuttle-box relative to the transferrer to shift the position of the cells, and then return them to normal position and means to prevent movement of the shuttle-box relative to the 40 transferrer in case the shuttle is not properly boxed.

27. In a filling replenishing loom, the combination of the lay and shuttle-boxes, a hopper for a series of shuttles, a transferrer, 45 means for causing the transferrer to move toward the lay and means for temporarily locking the transferrer to and for movement with the lay on call for filling replenishment to effect a transfer of a fresh 50 shuttle to the shuttle-box while the loom continues the weaving operation, and means to free the transferrer from movement with the lay and return it to normal position after the transfer. 55

In testimony whereof, I have signed my name to this specification, in the presence of two subscribing witnesses.

WILLIAM H. BAKER.
